UNITED STATES PATENT OFFICE.

EDWARD S. FIELD, OF METCHOSIN, CANADA.

DESIGN FOR A HOLDER-BRACKET.

SPECIFICATION forming part of Design No. 24,008, dated February 5, 1895,

Application filed January 5, 1895. Serial No. 533,973. Term of patent 7 years.

To all whom it may concern:

Be it known that I, EDWARD S. FIELD, of 5
Metchosin, in the Province of British Columbia
and Dominion of Canada, have invented
and produced a new and original Design for
a Holder-Bracket, of which the following is a
specification.

The design relates to brackets for holding
brooms and the like.

10 Reference is to be had to the accompanying
drawing, in which the figure represents a
perspective view of a holder bracket embody-
ing my new design.

15 The leading feature of my design consists
in the holder bracket having at the front the
arms *a* that curve toward each other, their

outer surfaces *a'* being vertical, and also
rounding transversely, while the inner sur-
faces of the arms merge into each other pre-
senting an opening having vertical walls to-
ward the bottom as at *a²*, but flaring outward
at the top from the vertical plane as at *a³*, the
bracket further having side projections *b* at
the bases of the arms *a*, the said projections
presenting angular figures. 20

I claim—

The design for a holder bracket herein
shown and described.

EDWARD S. FIELD.
